CAM FOR A FASTENING MECHANISM FOR CONTAINER DOORS

Barry Stanley Morris, Walsall England, assignor to The Blowitch Lock and Stamping Company, Limited, Staffordshire, England

Filed Jan. 31, 1975, Ser. No. 546,115

Term of patent 14 years

Int. Cl. D8—07

U.S. CL. D8—137

FIG. 1.

FIG. 2.

FIG. 3.

FIG. 4.

FIG. 5.

FIG. 6.

FIG. 7.

FIG. 8.

FIG. 1 is a top perspective view from one end and one side of a cam for a fastening mechanism for container doors showing my new design;

FIG. 2 is a top perspective view from the opposite end and opposite side;

FIG. 3 is an elevation of the said opposite side;

FIG. 4 is a section on line 4—4 of FIG. 3;

FIG. 5 is a top plan;

FIG. 6 is an underneath plan;

FIG. 7 is an elevation of said one end; and

FIG. 8 is an elevation of said opposite end of the cam.

I claim:

The ornamental design for a cam for a fastening mechanism for container doors, as shown.
